UNITED STATES PATENT OFFICE.

OWEN REDMOND, OF ROCHESTER, NEW YORK, ASSIGNOR TO RUFUS F. OSGOOD, OF SAME PLACE.

IMPROVEMENT IN PACKINGS FOR OIL-WELLS.

Specification forming part of Letters Patent No. 59,319, dated October 30, 1866.

To all whom it may concern:

Be it known that I, OWEN REDMOND, of Rochester, in the county of Monroe and State of New York, have invented certain new and useful Improvements in Packings for Oil-Wells; and I do hereby declare that the following is a full and exact description thereof, reference being had to the accompanying drawings, making part of this specification.

Figure 1 is a central vertical section of my improved packing device, situated in the shaft of an oil-well and around the elevating-tube; Fig. 2, an elevation of the same; Fig. 3, a cross-section in the plane of line $x x$, Fig. 1.

Like letters of reference indicate corresponding parts in all the figures.

In oil-wells it is necessary to employ a packing device of some kind around the elevating-tube, and filling the area of the shaft or bore of the well, in order to prevent the surface-water from running in with the oil.

The ordinary packing is what is known as the "seed-bag," a bag secured fast to the tubing at a suitable position and filled with flax-seed, which, when the tubing is adjusted in place, swells on becoming wet, and packs both around the tube and against the walls of the well.

The great difficulty with this kind of packing is that it is non-adjustable, so that if it is fixed in place too high or too low, it cannot be changed or adjusted without removing the tubing from the well, a labor of great difficulty and risk, as the well is liable to become injured thereby, as is well known. Another difficulty is that the seed soon rots, and in order to replace the packing the tubing must be removed.

It is the object of my improvement to remedy these difficulties; and the invention consists, primarily, in the employment of an adjustable packing device sliding up and down on the central elevating-tube, being operated from the top of the well by wires, rods, chains, cords, or equivalent, and packing both the shaft or bore of the well and the elevating-tube, so as to prevent the passage of water downward. The essential advantages attained are that the packing can be raised and lowered to adapt it to any desired position, or can be entirely removed from the well without raising the elevating-tube.

As represented in the drawings, A is the shaft or bore of the well, and B the elevating or oil tube.

The packing device may be of any construction that will secure the following effects, viz., slide up and down on the central elevating-tube, so as to be fixed in position at any desired place without removing the tubing, and pack both the shaft and tube. I prefer that represented in the drawings, which is of the following construction:

Around the elevating-tube B fits a cylinder or tube, C, of suitable length, sliding freely up or down over the oil-tube, and preferably made of considerable weight. To the lower portion is attached, at a , in any suitable manner, a dish-shaped disk or rim, b , of buckskin, leather, or other suitable flexible material, which is for the purpose of packing outward against the walls of the well, when the proper mechanical parts are applied to operate it, as will presently be described.

To the top of the cylinder C is attached a flexible collar, c , which packs against the oil-tube B, as clearly represented. The weight of the packing device is made sufficient to carry it down over the oil-tube easily, and in raising it will usually come up without difficulty; or, if desired, small wires or cords $d d$, Fig. 2, may be employed for the purpose. I prefer to insert a small ring, e , in the upper end to keep it open.

It will be seen that if both the disk b and collar c are packed tightly no water can escape through from above to the oil below.

Around the cylinder C, near its upper end and between shoulders $f f$, is situated a collar or sleeve, D, turning loosely, and having at its top a beveled cog-rim, g , and on its side a screw-thread, h .

Outside this collar is situated another collar or sleeve, E, which serves as a nut, its interior surface being also cut into a screw-thread, i , that engages with h . This latter collar can move vertically up or down, but is not allowed to turn, by reason of arms $k k$, which pass loosely down through sockets in a circular wedge, G, and have heads $l l$ on their lower ends.

The wedge G is simply a hollow head whose lower edge is beveled, as shown, and which slides freely up and down, but is prevented

from turning by means of a feather, *m*, Fig. 2, that fits in a corresponding groove in the wedge or some equivalent device. The lower edge of the collar *E* rests on top the wedge to force it down, and the lower beveled edge of the wedge rests in the upper open end of the flexible dish-shaped disk *b*.

Thus it will be perceived that if the collar *D* be turned, the collar *E* will be forced down as a nut, and consequently, also, the wedge *G*, which expands the packing *b* out against the sides of the well.

In raising to release the packing, the heads *ll* of the arms *k k* strike shoulders *m' m'* of the wedge on the under side, and thereby draw it up.

On a bearing, *n*, near the top of the cylinder *C*, is situated a beveled pinion, *o*, which gears with the cog-rim *g*. This pinion is fast with a small wheel or disk, *p*, which receives motion either by means of a wire or cord, *q*, wound once or twice around in a groove in its periphery, as indicated in Fig. 2, or by a chain engaging with spurs on its periphery, as indicated in Fig. 1, or in some similar manner. In either case the wire, cord, or chain is double, and extends to the top of the well. By this means it will be seen that the wedge *G* may be tightened or loosened at any time by simply operating the wire or chain, provided the cylinder *C* is fastened securely to the oil-tube.

I secure the cylinder to the oil-tube at any desired position by means of a screw, *r*, whose point, passing through the cylinder, strikes against the oil-tube, and, when tightened up, draws the cylinder so tightly to the tube that it cannot slip. The head of the screw is made of considerable size and of a form similar to the wheel *p*, and has a similar wire, cord, or chain, *s*, passing around it and extending to the top of the well. This device is very simple and effective, being easily operated and always holding the packing device securely in place.

In addition to operating the parts *p r*, the wires or chains may also serve to lower or raise the packing device in the well.

The arrangement that I have above described is but one simple form of an adjustable packing device for oil-wells. Many others may be used that involve the same essential principle.

Notwithstanding similar devices have been patented, I believe myself to be the first inventor of a packing device sliding on a central tube capable of adjusting to a greater or less depth, being operated from the surface by means of wires, rods, cords, or chains, and

packing both against the walls of the well and the oil-tube. It will be perceived that in my case the tubing is adjustable up and down within the packing, as well as the packing upon the tubing. To accomplish this adjustment it is only necessary to release or expand the packing, as before described, when the tubing is free to slide up or down. The advantage of such a device is obvious.

The packing may be adjusted to any position, higher or lower, in a few minutes, or entirely removed. Thus, if it should be placed at first in a wrong position, the true position can readily be determined by experiment, and the packing soon fixed there. Or if the packing should become worthless, it can be replaced at any time without difficulty and without removing the tubing, a matter of the utmost importance, since the removing of the tubing frequently destroys the flow of oil. Where the ordinary seed-bag is employed, if it is fixed in a wrong position, or if it becomes worthless, the whole tubing must be raised to remedy the difficulty, and the remedy is frequently worse than the difficulty itself.

An expanding packing is common in pumps and engines, fitting in an open cylinder; but such is not the equivalent of my device, which fits not simply in an open cylinder, but in a bore or shaft, and slides up and down on a central tube, and packs both the shaft and the tube. In order to operate several hundred feet below the surface of the earth a device of a peculiar and original kind is required.

What I claim as my invention, and desire to secure by Letters Patent, is—

1. A packing device for artesian wells, packing both the tubing and the sides of the well, when the said device is capable either of being adjusted higher or lower upon the tubing, or, vice versa, the tubing adjusted higher or lower within the packing, substantially as specified.

2. The combination of the hollow wedge *G* and screw-collars *D E*, for the purpose of expanding the packing-disk *b*, substantially as described.

3. Securing the packing device to the oil-tube at any position by means of the screw *r*, provided with a head or rim around which passes a wire, cord, or chain, *s*, substantially as specified.

In witness whereof I have hereunto signed my name in the presence of two subscribing witnesses.

OWEN REDMOND.
